UNITED STATES PATENT OFFICE.

JOHN SCHAAF AND WILLIAM TOMASKOFF, OF NEWARK, NEW JERSEY.

LADDER ATTACHMENT.

Application filed February 2, 1921. Serial No. 441,759.

To all whom it may concern:

Be it known that we, JOHN SCHAAF and WILLIAM TOMASKOFF, both citizens of the United States, and residents of Newark, in 5 the county of Essex and State of New Jersey, have invented new and useful Improvements in Ladder Attachments, of which the following is a specification.

This invention relates in general to ladder terminals or attachments, and more particularly to a ladder attachment adapted to be applied to the upper end of the stile of a ladder to prevent both lateral and longitudinal slipping or sliding of the ladder along 15 the wall of a building or other upright surface with which the ladder is used.

The objects of the invention are to provide a ladder attachment of the character described embodying novel features of construction comprising a pointed or other bearing member for positively engaging the wall of a building or the like, and means for detachably mounting the said pointed member on the end of the stile of a ladder; 20 to provide an improved construction in which the bearing member has a limited movement relatively to the ladder, so that the ladder may flex or bend under the weight of a person ascending or descending without disturbing the engagement of the bearing member with the wall or the like thereby eliminating scratching or other marring of the wall by the bearing member; to provide 25 a ladder attachment comprising a body portion adapted to be detachably secured to the stile of a ladder, and a bearing member pivotally mounted on said body portion to swing in a plane longitudinally of the ladder, said body portion being formed with 30 spaced stops to limit said swinging; to provide such a ladder attachment having a spring to normally influence said bearing member toward a position substantially midway between said stops, and to obtain other 35 results and advantages as may be brought out by the following description.

Referring to the accompanying drawings, in which like numerals of reference indicate the same parts throughout the several views, 40 Figure 1 is a side elevation of a ladder attachment constructed in accordance with our invention, showing the manner of applying the same to the stile of a ladder indicated by dot and dash lines; 45 Figure 2 is a front end elevation thereof; Figure 3 is a top plan view thereof;

Figure 4 is a fragmentary longitudinal sectional view through the forward end of the body portion, the bearing member being shown in side elevation, and 60

Figure 5 is a perspective view of the portion of a ladder and a wall or the like, showing the manner of using our invention.

In the embodiment of the invention shown in the drawings the numeral 1 designates 65 the body portion of the attachment which may be conveniently formed of a single strip of sheet material bent into a U-shape and having secured between the extremities of the arms thereof a block 2. The dimensions 70 of the body portion 1 are such as to enable the same to be loosely slipped over the end of the stile 3 of a ladder. For the purpose of clamping the body portion 1 to the stile 75 of the ladder the block 2 may be provided with a threaded opening 4 in which is mounted a clamping screw 5, the inner end of which has a swivel connection 6 with a toothed clamping or dog plate 7. The outer end of the screw 5 is provided with a handle 80 bar 8 slidably mounted in the head 5^a of the screw to slide transversely thereof.

The end of the body portion 1 opposite the clamping screw 5 carries the bearing member 9 which is preferably an isosceles 85 triangular block. This bearing member 9 is pivotally mounted on a pivot pin 10 in a housing 11 secured to the body portion 1 in any suitable manner as by riveting, the forward end of the housing being provided with 90 an opening 12 through which projects the bearing member 9. The pivot pin 10 passes through the bearing member 9 adjacent the short side or base thereof and substantially centrally of the length of said side. Thus 95 the sharpest angle or apex of the bearing member projects outwardly through the opening 12 in the housing 11, and the outer end of the bearing member may have its sides beveled as at 13 to provide a sharp 100 point for engagement with a wall or the like with which the ladder is to be used. The outer end of the bearing member 9 is normally positioned substantially centrally of the opening 12 by means of a flat spring 14 105 which engages the short side of the bearing member, the said spring being spaced from the end of the body portion 1 by means of the laterally bent ends 15 of the spring. It will thus be seen that the bearing member 9 110 may swing in the opening 12, the extent of the movement being determined by the end

walls of said opening, the spring 14 being flexed during the swinging of the bearing member as indicated by dot and dash lines in Figure 4.

5 In the use of the device one attachment is applied to each stile of the ladder near the upper end thereof, as shown in Figure 5, the clamping screw 5 and plate 7 serving to securely but detachably fasten the foot to the stile of the ladder. The pointed ends of the bearing members 9 thus engage the wall or other upright surface with which the ladder is being used to prevent longitudinal or lateral sliding or slipping of the ladder on 10 the wall. The slight longitudinal movement or flexing of the ladder due to the weight of a person ascending or descending the same is compensated for by the swinging of the bearing member 9 on the pivot pin 10, thus 15 20 the engagement of the bearing member 9 with the wall is undisturbed, thereby eliminating scratches or other marring on the wall which would be incident to sliding of the bearing member were the same in fixed 25 relation to the stile of the ladder.

Other forms of clamping means for securing the ladder foot to the stile of a ladder may be utilized instead of the clamping screw illustrated, such as for instance, cam 30 levers, or the like.

While we have shown and described one possible embodiment of our invention, it will be understood that this is for the purpose of illustrating the principles thereof only, 35 and that many modifications and changes can be made in the detail construction of the same without departing from the spirit or scope of the invention.

Having thus described the invention, what 40 we claim is:

1. A ladder attachment including a body portion adapted to be attached to the stile of a ladder, a bearing member pivotally mounted on said body portion to engage a 45 wall or the like with a single point contact to prevent slipping of the ladder, said bearing member being mounted to swing in a

plane longitudinally of the ladder to allow the ladder to move slightly longitudinally without moving the point of the engagement 50 of said bearing member with the wall, and yielding means tending to hold said bearing member against movement.

2. A ladder attachment including a body portion adapted to be attached to the stile 55 of a ladder, a bearing member pivotally mounted between its ends on said body portion, one end of said member being adapted to engage a wall or the like to prevent slipping of the ladder, said bearing member being mounted to swing in the plane longitudinally of the ladder to allow the ladder to move longitudinally without moving the point of engagement of the bearing member with the wall, and yielding means engaging 60 the other end of said bearing member tending to hold the same against movement on its pivot.

3. A ladder attachment including a body portion adapted to be attached to the stile 70 of a ladder, a bearing member pivotally mounted between its ends on said body portion and having a flat end, the end of said member opposite said flat end being adapted to engage a wall or the like to prevent slipping of the ladder, and a substantially flat spring interposed between said flat end of the bearing member and the body portion tending to hold said bearing member against 75 swinging on its pivot.

4. A ladder attachment including a body portion adapted to be attached to the stile of a ladder and having an opening therein, a bearing member pivotally mounted on said body portion and projecting through said opening to engage a wall or the like to prevent slipping of the ladder, the edges of said opening serving as stops to limit the movement of said bearing member on its pivot, and yielding means for normally holding 80 said bearing member at a point between said stops.

JOHN SCHAAF.
WILLIAM TOMASKOFF.
